UNITED STATES PATENT OFFICE.

CHARLES J. AIRENFIELDT, OF NEW YORK, N. Y.

DESIGN FOR A CRACKER-BOWL.

SPECIFICATION forming part of Design No. 24,200, dated April 16, 1895.

Application filed November 17, 1894. Serial No. 529,192. Term of patent 7 years.

To all whom it may concern:

Be it known that I, CHARLES J. AIRENFIELDT, a citizen of the United States, residing in the city of New York, county and State of New York, have invented and produced a new and original Design for a Cracker-Bowl, of which the following is a specification.

The accompanying drawings represent a cracker bowl embodying my design, and consist of Figure 1, which is a perspective view of said bowl with the ornamentation displayed upon it in relief, and Fig. 2, which is a plain view of the cover of said bowl displaying the ornamentation.

15 The essential feature of my design consists of a cracker bowl provided with a combination arabesque and escaloped ornamentation as shown in the accompanying drawings.

In Fig. 1, A is the arabesque ornamentation. 20 B is the escaloped ornamentation. C is the trefoil shaped edge of the bowl. D D D are the greater segmentations, D' the lesser ones.

In Fig. 2, A is the arabesque ornamentation. B is the escaloped ornamentation. C is the 25 trefoil shaped edge of the cover, and D D D are the greater segmental indentations, D' the lesser; and E is the knob. F is the plain exterior surface. The bowl and cover have three greater segmentations which begin at 30 the top in the bowl and terminate at the bottom. These greater segmentations cause the general contour of the bowl to assume a trefoil shape. This is more plainly shown in the lip or edge. A series of lesser segmentations 35 extend from the bottom upward and merge

into the plain exterior surface of the bowl. These lesser segmental lines divide a series of groups of double escaloped ornamentations overlapping each other, which have a sharply defined upper edge, and at their lower part merge into the foot of the bowl. Both the greater and lesser segmental lines have a spiral twist. On each of the segments formed by the greater segmental lines is lodged on the upper part an arabesque ornamentation 45 in relief. This ornamentation is formed in a series of curved lines, which begin at a point near the edge of the bowl and extend downward in diminishing curves toward the center plain exterior surface. 50

The cover of the bowl has also three greater segmental lines, and a series of lesser ones dividing groups of escaloped ornamentations. These escaloped ornamentations are like those on the bowl double lying one over the other. 55 They are sharply accentuated on their outer edge, and merge into the plain exterior surface of the cover.

An arabesque ornamentation is lodged in the central part of the cover which is in the 60 center aggregated and drawn up to form a knob.

I claim—

The design for a cracker bowl, substantially as herein shown and described.

CHARLES J. AIRENFIELDT.
